UNITED STATES PATENT OFFICE

2,567,620

AUTOMATIC STEADY REST FOR GRINDING MACHINES

Herbert A. Silven, Worcester, Mass., assignor to
Norton Company, Worcester, Mass., a corpora-
tion of Massachusetts

Application December 21, 1948, Serial No. 66,419

2 Claims. (Cl. 51—238)

1

The invention relates to grinding machines and more particularly to an automatically actuated steadyrest for cylindrical grinding machines.

One object of the invention is to provide a simple and thoroughly practical automatically operated steadyrest. Another object is to provide an automatically operated steadyrest in which the steadyrest shoe is advanced automatically into operative engagement with the work piece to be ground. Another object is to provide a steadyrest in which the steadyrest shoe is automatically advanced into operative engagement with the work piece to be ground and in which the shoe is automatically maintained in supporting engagement with the work piece during grinding as the work piece is reduced in size. Another object is to provide an automatically operated two-shoe type steadyrest in which both of the work steadyng shoes are automatically advanced into engagement with the work piece to be ground and are automatically maintained in supporting engagement therewith during the entire grinding operation.

A further object is to provide an automatically operated steadyrest which operates in timed relation with the feeding movement of the grinding wheel so that when the grinding wheel is advanced at the start of a grinding operation, the work steadyng shoes are moved automatically into supporting engagement with the work piece to be ground and are automatically maintained in steadyng engagement therewith during the entire grinding operation. Another object is to provide an automatically operated steadyrest which operates in timed relation with the movement of the grinding wheel so that when the grinding wheel is moved to an inoperative position after a grinding operation has been completed, the steadyrest shoes are moved automatically and simultaneously to an inoperative position. Other objects will be in part obvious and in part pointed out hereinafter.

The invention accordingly consists in the features of construction, combinations of elements, and arrangements of parts, as will be exemplified in the structure to be hereinafter described, and the scope of the application of which will be indicated in the following claims.

In the accompanying drawing in which is shown one of various possible embodiments of the mechanical features of this invention,

Fig. 1 is a hydraulic piping diagram showing the operation of the improved steadyrest operatively connected to operate in timed relation with the wheel feeding mechanism;

2

Fig. 2 is a side elevation of the improved steadyrest;

Fig. 3 is a fragmentary front elevation, on an enlarged scale, of the steadyrest showing part 5 of the actuating mechanism therefor;

Fig. 4 is a fragmentary horizontal sectional view, on an enlarged scale, taken approximately on the line 4—4 of Fig. 2, through the horizontal shoe adjusting mechanism; and

Figure 5 is a fragmentary view, on an enlarged scale, showing the rotatable work support.

As illustrated in the drawing, a grinding machine is provided having a longitudinally movable work table 11 which is provided with a rotatable work support comprising a headstock 6 and a footstock 7 having work supporting centers 8 and 9, respectively, for rotatably supporting a work piece to be ground. The work table 11 also supports a steadyrest frame 12 having a pair of work steadyng shoes 13 and 14 to support and steady a work piece 15 during a grinding operation. The steadyrest shoe 13 is supported on the right hand end of a horizontally 20 adjustable slide 16 which slides within an aperture 17 formed within the steadyrest frame 12. An adjusting screw 18 is threaded into a threaded aperture 19 formed within the slide 16. The screw 18 is rotatably supported in a bearing 20 which is fixedly mounted within the frame 12. A manually operable actuating knob 21 is mounted on the left hand end of the screw 18 to facilitate a manual adjustment of the shoe 13.

The steadyrest shoe 14 is mounted on the right 35 hand end of a pivotally mounted arm 25 which is supported by a stud 26 on the frame 12. To facilitate adjustment of the arm 25 and shoe 14, a cam 27 is formed on a transversely movable slide 28. The cam 27 engages a roller 29 which is supported by a stud 30 on the arm 25. An adjusting screw 31 is screw threaded into a threaded aperture 32 formed within the slide 28. The screw 31 is rotatably supported by a bearing 33 which is fixedly mounted within the steadyrest frame 12. A manually operable knob 34 is mounted on the left hand end of the screw 31 and serves to facilitate manual adjustment of the shoe 14 relative to the work piece 15.

The steadyrest frame is preferably shaped with suitable bearing surfaces to mate with correspondingly shaped surfaces on the table 11. The steadyrest frame 12 is provided with a clamping arm 35 which is actuated by a manually operable clamping lever 36 so that the steadyrest 55 may be readily clamped on or removed from the table 11 when desired.

In order to facilitate automatic operation of the steadyrest shoes 13 and 14 a suitable mechanism is provided for automatically advancing the steadyrest shoes at the start of a grinding operation into engagement with the work piece 15 and to maintain them in contact therewith during the grinding operation. In the preferred construction, a spring actuated means is provided for causing the steadyrest shoes 13 and 14 to advance into engagement with the work piece 15. The compression of the spring is sufficient to feed the shoes 13 and 14 and to maintain them in supporting engagement with the work piece 15 as it is reduced in size due to grinding. A hydraulically operated mechanism is provided for withdrawing the shoes 13 and 14 to an inoperative position after a grinding operation has been completed. As illustrated in the drawings a hydraulic cylinder 40 is mounted on the left hand end of the steadyrest frame 12. The cylinder 40 contains a slidably mounted piston 41 which is connected to one end of a piston rod 42. A block 43 is fixedly mounted on the upper end of the piston rod 42 and is provided with a rack 44 which meshes with a pinion 45 formed on the shoe adjusting screw 18. A compression spring 46 surrounds the piston rod 42 and is interposed between the piston 41 and the upper end cap of the cylinder 40. The compression of the spring 46 serves normally to exert a downward pressure on the piston 41 which tends to rotate the shoe adjusting screw 18 to advance the work shoes 13 toward the work piece 15. An adjustable stop screw 47 carried by the block 43 serves to limit the downward movement of the piston 41 and thereby to determine the forward and final position of the work steadyrest shoe 13. A fluid pipe 48 is provided to convey fluid under pressure into a cylinder chamber 49 to cause an upward movement of the piston 41 which in turn serves to rotate the shoe adjusting screw 18 in the reverse direction to cause the work steadyrest shoe 13 to move to an inoperative position. An adjustable stop screw 50 serves to limit the upward movement of the piston 41 and the block 43 to determine the inoperative position of the steadyrest shoe 13.

A similar mechanism is provided for controlling the movement of the work steadyrest shoe 14 to and from an operative position. This mechanism comprises a cylinder 51 mounted on the left hand end of the steadyrest frame 12. The cylinder 51 contains a slidably mounted piston 52 which is connected to one end of a piston rod 53. A block 54 is fixedly mounted on the lower end of the piston rod 53 and is provided with a rack 55 which meshes with a pinion 56 formed on the shoe adjusting screw 31. A compression spring 57 surrounds the piston rod 53 and is interposed between the piston 52 and the lower end cap of the cylinder 51. The compression of the spring 57 serves normally to exert an upward pressure on the piston 52 which tends to rotate the shoe adjusting screw 31 to move the work steadyrest shoe 14 toward the work piece 15. An adjustable stop screw 58 carried by the block 54 is arranged to engage the end cap at the lower end of the cylinder 51 to determine the forward feeding position of the work steadyrest shoe 14. A fluid pipe 59 serves to admit fluid under pressure to a cylinder chamber 60 formed in the upper end of the cylinder 51. When fluid under pressure is admitted through the pipe 59 into the cylinder chamber 60, it causes a downward movement of the piston 52 which rotates the shoe adjusting screw 31 in the reverse direc-

tion to withdraw the work steadyrest shoe 14 to an inoperative position. An adjustable stop screw 61 is arranged in the path of movement of the block 54 and serves to facilitate limiting the movement of the shoe 14 to an inoperative position.

In order to attain one of the objects of this invention, it is desirable to provide suitable connections between the wheel feeding mechanism and the steadyrest so that when the grinding wheel is advanced toward the work at the start of a grinding operation the steadyrest shoes 13 and 14 automatically are moved into engagement with the work piece 15 and automatically are maintained in supporting engagement therewith as the grinding operation proceeds. As illustrated diagrammatically in the drawings, a transversely movable wheel slide 70 is provided for supporting a rotatable grinding wheel 71. The grinding wheel 71 is preferably driven by means of a motor 72 mounted on the upper surface of the wheel slide 70. The motor 72 is provided with a pulley 73 which is connected by multiple V-belts 74 with a pulley 75 mounted on the end of the wheel spindle.

To facilitate feeding the wheel slide 70 toward and from the work piece 15, a half nut 76 is mounted on the underside of the wheel slide 70 which meshes with a rotatable feed screw 77. The wheel feeding mechanism diagrammatically disclosed in Fig. 1 is substantially the same as that shown in the prior United States Patent No. 2,151,660 to B. H. Goehring dated March 21, 1939, to which reference may be had for details of disclosure not contained herein. The feed screw 77 may be rotated manually as illustrated in the prior patent above referred to if desired. To facilitate automatic feeding of the grinding wheel slide 70, a hydraulic cylinder 78 is provided which contains a slidably mounted piston 79 which is fixedly mounted on a double end piston rod 80. The left hand end of the piston rod 80 is connected to a slidably mounted sleeve 81 which connects the piston rod 80 with the feed screw 77. The sleeve 81 permits a rotary motion of the feed screw 77 while the piston rod 80 remains stationary.

The piston and cylinder serve to cause a rapid movement of the wheel slide 70 in either direction. In order to facilitate slowing down the rapid approaching movement of the wheel slide 70 to a predetermined grinding feed, a dash pot feed regulator 82 is provided which serves to adjustably retard the movement of the piston 79 so as to obtain the desired and predetermined infeeding movement of the slide 70 and grinding wheel 71. This dash pot feed regulator will not be described in detail since this mechanism is identical with the dash pot feed regulator which is fully described and illustrated in the above referred to prior U. S. patent.

A feed control valve 83 is provided for controlling the admission to and exhaust of fluid from the cylinder 78. The control valve 83 is preferably a piston type valve comprising a valve stem 84, the left hand end of which is connected to a rock arm 85. A solenoid 86 serves when energized to shift the valve stem 84 toward the left (Fig. 1). A compression spring contained within the casing of the valve 83 serves normally to maintain the valve stem 84 in the position as illustrated in Fig. 1. A plurality of valve pistons 87, 88, 89 and 90 are formed integral with the valve stem 84.

A fluid pressure system is provided for supply-

ing fluid under pressure to operate both the wheel feeding mechanism and the steadyrest shoes. This system may comprise a reservoir 91 which may be contained within the base of the grinding machine. Fluid is drawn from the reservoir 91 through a pipe 92 by means of a motor driven pump 93. The pump 93 forces fluid under pressure through a pipe 94 to the control valve 83. In the position of the valve 83 (Fig. 1) fluid under pressure in the pipe 94 passes through a valve chamber formed between the valve pistons 88 and 89 and through a passage into a cylinder chamber 95 to cause the piston 79 to move toward the right so as to move the wheel slide 70 and the grinding wheel 71 to an inoperative position. During this movement of the piston 79, fluid within a cylinder chamber 96 formed at the right hand end of the cylinder 78 exhausts through a passage into a valve chamber formed between the valve pistons 87 and 88 and exhausts through a pipe 115 and a throttle valve 116 into the reservoir 91. The throttle valve 116 provided in the exhaust pipe 115 serves to facilitate regulation of the exhaust of fluid from the cylinder chamber 96 to control the rate of movement of the grinding wheel 71 to an inoperative position. A relief valve 97 is provided to facilitate maintaining the desired operating pressure within the fluid system. The relief valve 97 is an adjustable type relief valve whereby excess fluid under pressure may be returned directly to the reservoir 91.

In order to facilitate automatic operation of the steady-rest shoes 13 and 14, a suitable fluid connection is provided between the control valve 83 and the cylinders 40 and 51. This connection may comprise a pipe 98 which is connected between the valve 83 and the pipes 48 and 59. It is desirable to provide an independent manual control for the steadyrest shoes 13 and 14 so that the work steadyng shoes may be manually controlled if desired or may be automatically moved to and from operative positions in timed relation with the feeding movement of the grinding wheel 71. A valve 99, as shown in Fig. 1, is provided in the pipe 98 to facilitate cutting off the flow of fluid from the feed control valve 83. A manually operable control valve 100 is provided to facilitate manual control of the steadyrest shoes 13 and 14 when desired. The control valve 100 is a piston type valve comprising a valve stem 101 having valve pistons 102, 103 and 104 formed integral therewith. A manually operable control lever 105 is provided for manually shifting the valve stem 101. Fluid under pressure from the pump 93 is connected to a pipe 106 to convey fluid under pressure to a valve chamber located between the valve pistons 103 and 104. An exhaust pipe 107 is provided to connect the valve chamber located between the valve pistons 102 and 103 with the reservoir 91. A pipe 108 is provided to connect the valve 100 with the pipe 98. The valve 99 is arranged, as shown in Fig. 1, so that the control valve 100 may be connected to operate the steadyrest shoes when desired.

As shown in the drawings, the valve 99 is closed so that fluid cannot flow from the control valve 83 to the steadyrest. The valve 109 is positioned so that fluid contained within the cylinder chambers 49 and 60 may exhaust through the pipes 48 and 59 respectively through the pipe 98, through the valve 99, through the pipe 108, through the valve 100 into the reservoir 91 so that the released compression of the springs 46

and 57 serves to rotate the shoe adjusting screws 18 and 31 respectively to move the work steadyng shoes 13 and 14 into operative engagement with the work piece 15 and to feed the shoes 13 and 14 as the work piece 15 is reduced in diameter due to grinding so that the work piece 15 is at all times supported and steadied by the shoes 13 and 14. When it is desired to withdraw the shoes 13 and 14 to an inoperative position, the control lever 105 is shifted in a counter clockwise direction to shift the valve stem 101 toward the left (Fig. 1) so that fluid under pressure in the pipe 106 may pass through the valve 100, through the pipe 108, through the valve 99 into the cylinder chambers 49 and 60 to move the piston 41 upwardly and the piston 52 downwardly against the compression of the springs 46 and 57 respectively so as to rotate the shoe adjusting screws 18 and 31 respectively to move the shoes 13 and 14 to inoperative positions after a grinding operation has been completed.

When an automatic grinding operation of the steadyrest shoes 13 and 14 is desired, the valve 109 is turned 90°, in a clockwise direction (Fig. 1), so as to render the manual control valve 100 inoperative and the valve 99 is opened so that fluid under pressure may pass through or exhaust through the pipe 98 to or from the cylinder chambers 49 and 60. In this position of the valve 99, the passage of fluid to and exhaust of fluid from the steadyrest cylinders 40 and 51 is controlled by the feed control valve 83. In the position of the valve 83 as illustrated, fluid under pressure from the pump 93 passing through the pipe 94 into the valve chamber formed between the valve pistons 88 and 89 may pass through the pipe 98 and through the pipes 48 and 59 into the cylinder chambers 49 and 60 to cause the steadyrest shoe adjusting screws 18 and 31 to be rotated to automatically withdraw the work steadyng shoes 13 and 14 to inoperative positions simultaneously with the admission of fluid into the cylinder chamber 95 to cause a rearward movement of the piston 96 and the grinding wheel 71 to an inoperative position. Similarly when a forward feeding movement of the grinding wheel 71 is initiated by energization of the solenoid 86, the valve 83 is shifted toward the left (Fig. 1) so that fluid under pressure in the pipe 94 passes into the valve chamber located between the valve pistons 88 and 89 and through a passage into the cylinder chamber 96 to cause a forward feeding movement of the piston 79, the wheel slide 70 and the grinding wheel 71. At the same time fluid contained within the steadyrest cylinder chambers 49 and 60 may exhaust through the pipes 48 and 59 respectively, and through the pipe 98, through a valve chamber located between the valve pistons 89 and 90 and out through the exhaust pipe 115 into the reservoir 91. The exhaust of fluid from the cylinder chambers 49 and 60 serves to release the compression of the springs 46 and 57 so as to cause a downward movement of the piston 41 and an upward movement of the piston 52 to rotate the shoe adjusting screws 18 and 31 respectively to cause the work steadyng shoes to move into operative engagement with the work piece 15 to be ground and to maintain the shoes 13 and 14 in operative engagement therewith during the entire grinding operation as the work piece 15 is reduced in size. It will be readily apparent from the foregoing disclosure that by manipulation of the valve 99, the steadyrest 12 may be operated either under a manual control or automatically in timed relation with

the feeding movement of the grinding wheel 11.

The operation of this improved steadyrest will be readily apparent from the foregoing disclosure.

It will thus be seen that there has been provided by this invention apparatus in which the various objects hereinabove set forth together with many thoroughly practical advantages are successfully achieved. As many possible embodiments may be made of the above invention and as many changes might be made in the embodiment above set forth, it is to be understood that all matter hereinbefore set forth or shown in the accompanying drawings is to be interpreted as illustrative and not in a limiting sense.

I claim:

1. In a grinding machine having a longitudinally movable table, a rotatable work support, a transversely movable rotatable grinding wheel, means including a piston and cylinder to move said wheel transversely in either direction, a control valve therefor, and a steadyrest including a steadyrest base on said table, a work steadyng shoe adjustably mounted on said base, a nut and screw mechanism to adjust said shoe, means including a spring to rotate said screw to move the shoe into operative engagement with a work piece to be ground and to maintain the shoe in supporting engagement therewith as the work is reduced in size due to grinding, a piston and cylinder to rotate said screw in the opposite direction to move said shoe into an inoperative position, fluid connections between said latter cylinder and the feed control valve whereby the steadyrest shoe is actuated automatically in timed relation with the transverse movement of the grinding wheel, a normally inoperative valve to control the admission to and exhaust of fluid from the steadyrest cylinder, and a manually operable valve to render the connections between the feed control valve and the steadyrest cylinder inoperative and to render the normally inoperative valve operative when it is desired independently to control the operation of the steadyrest shoe.

2. In a grinding machine having a longitudinally movable table, a rotatable work support, a transversely movable rotatable grinding wheel, means including a piston and cylinder to move said wheel transversely in either direction, a feed control valve therefor, and a steadyrest including a steadyrest base on said table, a pair of work steadyng shoes adjustably mounted on said base, means including an independent nut and screw mechanism to adjust each of said shoes relative to said base, means including an independent spring operatively connected to actuate each of said nut and screw mechanisms automatically to move said shoes into engagement with the work and to maintain said shoes in operative engagement therewith during a grinding operation, means including an independent piston and cylinder to rotate each of said screws in the opposite direction independently to reposition said shoes after a grinding operation has been completed, fluid connections between both of said cylinders and the feed control valve whereby both of the shoes and the grinding wheel are automatically withdrawn simultaneously from engagement with the work, a normally inoperative manually operable valve to control admission to and exhaust of fluid from the steadyrest cylinders, and a valve to render the connections between the feed control valve and the steadyrest cylinders inoperative and to render the manually operable valve operative when it is desired manually to control the operation of the steadyrest shoes.
